UNITED STATES PATENT OFFICE.

ARTHUR BEAUCHEMIN, OF BURLINGTON, VERMONT, ASSIGNOR TO DRAPER CORPORATION, OF HOPEDALE, MASSACHUSETTS, A CORPORATION OF MAINE.

PICKER-STICK CHECK.

Application filed November 20, 1922. Serial No. 602,115.

To all whom it may concern:

Be it known that I, ARTHUR BEAUCHEMIN, a citizen of the United States, and resident of Burlington, county of Chittenden, and State of Vermont, have invented 5 an Improvement in Picker-Stick Checks, of which the following description, in connection with the accompanying drawing, is a specification, like characters on the drawing 10 representing like parts.

This invention relates to a picker stick check or mechanism for checking or retarding the picker stick by means of which the shuttle is picked back and forth across the 15 lay in a loom.

The invention has for its object to provide a mechanism of this type comprising an endless elongated flat stiff resilient and preferably metal loop.

20 The invention has for its further object to provide such a loop together with means for producing sufficient friction on the sides of the loop to give the requisite retardation to the loop when struck by the picker stick.

25 The invention has for its further object to provide a picker check mechanism in which the requisite retarding friction is secured by means acting to press in opposite directions against the opposite sides of an 30 endless elongated flat stiff resilient and preferably metal loop having a longitudinal sliding movement when struck by the picker stick.

The object of the invention has further to 35 provide a simple and efficient picker stick check mechanism readily adjustable to effect the requisite retardation of the picker stick.

These and other objects and features of 40 the invention will appear more fully from the accompanying description and drawing and will be particularly pointed out in the claims.

45 As the invention relates solely to the mechanism for checking the movement of the picker stick and as the general construction and operation of a loom including the picking mechanism is well known and familiar to those skilled in the art it is only 50 necessary here to illustrate and describe that portion of the loom directly concerned with the present invention. Furthermore as the picking mechanism may be and usually is the same at both sides of the loom it is only

necessary here to illustrate and describe the 55 construction at one side of the loom.

In the drawings:

Fig. 1 is a front elevation of the upper left hand side of the lay of a loom together with a preferred form of construction embodying the present invention;

Fig. 2 is a rear elevation of the construction shown in Fig. 1;

Fig. 3 is a view in transverse cross section partially broken away taken on the line 65 3—3 of Fig. 4;

Fig. 4 is a view in vertical cross section taken on the line 4—4 of Fig. 1.

The lay 1 is shown provided with the race plate 2 upon which the shuttle slides. At 70 the end the lay is also provided with the front wall 3 and the binder 4 constituting the rear wall of the box in which the shuttle is located when not on its flight across the lay. The picker stick 5 projects up through 75 a vertical slot in the lay and race plate and is swung or vibrated longitudinally of the lay in the usual manner to effect the movement of the shuttle. When the shuttle is boxed, as for example at the end of the loom 80 illustrated, the picker stick 5 stands in a position shown in the drawings. When the shuttle is to be picked across the loom to the opposite side the picker stick is swung with great force toward the center of the loom, 85 propelling the shuttle from the box and picking it across the lay. The movement of the picker stick toward the center of the lay must be retarded or checked after it has propelled the shuttle out of the box. When 90 the shuttle returns the picker stick is swung back and, as the shuttle enters the box, the movement of the shuttle is retarded or checked by the binder 4 and also by the tip 95 of the shuttle striking the picker stick, or preferably a buffer 7 secured to the picker stick. Thus the picker stick is returned with great force to the position shown in the drawings.

Various means have been provided for 100 checking or retarding the movement of the picker stick to its two positions. The picker stick checking mechanism is thus subject to most severe requirements. It must act uniformly and efficiently at each movement of 105 the picking mechanism under the most trying conditions. The force applied to the picker stick in picking the shuttle across the

loom and to the picker stick by the incoming shuttle is very great and very sudden and is constantly occurring during the operation of the loom often several times a second.

- 5 In the preferred form of construction herein illustrated as embodying the principles of this invention the checking mechanism is preferably supported from the lay. The lay presents the most convenient point 10 of support but, in the broader aspects of the invention, any suitable support may be utilized.

The mechanism comprises essentially an endless elongated flat stiff resilient loop 15 preferably formed of a flat strip of metal such as steel. In the construction illustrated this loop comprises the side 8 terminating in the curved, preferably semi-circular, ends 9 and 10. The side of the loop opposite the side 8 is formed by the overlapping ends 11 and 12 of the metal strip which are permanently secured together in any suitable manner as for example by the rivets 13. The inner surfaces of the curved ends 20 25 9 and 10 are provided with buffers 14 of leather or other suitable material to receive directly the blow of the picker stick.

This loop is supported and guided at its opposite sides and the requisite retardation 30 of the longitudinal movement of the loop is secured by pressing in opposite directions against the two longitudinal sides to give the requisite friction.

In the construction illustrated the supporting and guiding means comprise two brackets secured to and depending from the lay. The rear bracket 15 is preferably of angular shape fitting against the back and bottom of the lay and is secured thereto by a bolt 16. This bracket terminates at its lower end in a depending flat arm 17. One side, as 8, of the loop is mounted in a longitudinal recess in a long flat metal plate 18. A plate 19 of suitable friction material such 35 40 45 as leather is placed at the rear of the plate 18 and over this a second metal plate 20. The three plates 18, 19 and 20 are secured together as by the screws 21. The three plates with the interposed loop are adjustably and rigidly mounted on the depending arm 17 of the rear bracket as by means of a bolt 22 passed through a longitudinal slot 23 in the plates and a hole in the arm 17. This bolt is provided with suitable washers 50 55 60 65 24 and is locked in place by a nut 25.

The front bracket 26 is preferably of angular shape fitting against the front and bottom of the lay and is secured thereto by a bolt 27. In order to secure the requisite 65 70 75 80 85 opposing transverse pressure of the loop means are provided for adjusting a portion of one of the brackets toward and from the other and for that purpose the front bracket is made in two parts adjustable transversely of the lay. Consequently as illustrated the

bracket 26 is provided with a horizontal forwardly projecting bifurcated flange 28. To this flange is adjustably secured by means of the bolt 29 a flange 30 projecting forwardly from a flat depending arm 31 which is located directly opposite the depending arm 17 of the rear bracket. This arm 31 is formed to support and guide one side as 11, 12 of the loop and for that purpose is shown as provided with a ledge 32 at its bottom.

The operation of the mechanism will now be apparent. The picker stick in its movement strikes alternately the buffers 14 at the ends of the loop and in order to check or retard the movement of the picker stick the longitudinal movement which will be given to the loop causing it to slide longitudinally in the guiding and supporting means must be retarded to bring the picker stick to rest in the required manner. By adjusting the arm 31 of the front bracket toward or from the rear bracket or, in other words, by effecting a relative bodily transverse adjustment of said brackets, means are provided for compressing the loop transversely of its parallel sides thereby to produce sufficient friction on said sides to give the requisite retardation to the longitudinal movement of the loop. The degree of friction imparted to produce the retarding effect may be varied as required by varying the character of the surfaces thus pressed into contact with the opposite sides of the loop and such a means is illustrated in connection with the rear bracket in the provision of the plate 19 which is disclosed as made of leather or other suitable frictional material.

This mechanism is found in practice to produce the desired results and secure the requisite retarding action. The final position of the loop at the end of its movement in either direction may be definitely secured by permitting the ends of the buffers 14 to engage with the ends of the plate 18.

Having thus described my invention, what I claim as new and desire to secure by Letters Patent is:

1. A picker stick check for looms comprising a support, brackets mounted on the support, an endless elongated flat stiff resilient loop mounted to slide longitudinally between the brackets, and means for effecting relative bodily transverse adjustment of said brackets thereby to produce sufficient friction on the sides of the loop to give the requisite retardation to the loop when struck by the picker stick.

2. A picker stick check for looms comprising a support, an endless elongated flat stiff resilient loop mounted to slide longitudinally on the support, and means for compressing the loop transversely of its sides thereby to produce sufficient friction on the sides of the loop to give the requisite

retardation to the loop when struck by the picker stick.

3. In a loom having a lay, a picker stick check comprising a pair of oppositely disposed brackets secured to and depending from the lay, an endless elongated flat stiff resilient loop supported at its sides in said bracket and mounted to slide longitudinally therebetween, and means for adjusting one of said brackets toward and from the other thereby to produce sufficient friction on the sides of the loop to give the requisite retardation to the loop when struck by the picker stick.
- 10 4. In a loom having a lay, a picker stick check comprising a pair of oppositely disposed brackets secured to and depending from the lay, an endless elongated flat stiff resilient loop supported at its sides in said bracket and mounted to slide longitudinally therebetween, and means for effecting relative bodily transverse adjustment of said brackets thereby to produce sufficient friction on the sides of the loop to give the requisite retardation to the loop when struck by the picker stick.
- 15 5. In a loom having a lay, a picker stick check comprising a pair of oppositely disposed brackets secured to and depending from the lay, an endless elongated flat stiff resilient loop supported at its sides in said bracket and mounted to slide longitudinally therebetween, and means for adjusting one of said brackets toward and from the other thereby to produce sufficient friction on the sides of the loop to give the requisite retardation to the loop when struck by the picker stick.

posed brackets secured to and depending from the lay, an endless elongated flat stiff resilient loop supported at its sides in said bracket and mounted to slide longitudinally 20 therebetween, and means for adjusting one of said brackets toward and from the other thereby to produce sufficient friction on the sides of the loop to give the requisite retardation to the loop when struck by the 25 picker stick.

In testimony whereof, I have signed my name to this specification.

ARTHUR ^{his} X BEAUCHEMIN.
